UNITED STATES PATENT OFFICE.

FRANK H. MERRILL, DECEASED, LATE OF HENNEPIN COUNTY, MINNESOTA, BY
GRACE E. MERRILL, ADMINISTRATRIX, ASSIGNOR TO VEERAC COMPANY, OF
MINNEAPOLIS, MINNESOTA, A CORPORATION OF MINNESOTA.

FIRE-SCREEN FOR EXPLOSIVE-ENGINES.

1,363,801.

Specification of Letters Patent. Patented Dec. 28, 1920.

Original applicatin filed May 14, 1917, Serial No. 168,467. Divided and this application filed September 8, 1919. Serial No. 322,430.

To all whom it may concern:

Be it known that FRANK H. MERRILL, deceased, late citizen of the United States, and resident of the county of Hennepin and State of Minnesota, had invented certain new and useful Improvements in Fire-Screens for Explosive-Engines; that GRACE E. MERRILL, widow of the said FRANK H. MERRILL, has been duly appointed administratrix of the estate of said FRANK H. MERRILL; and that the said GRACE E. MERRILL, administratrix, does hereby declare the following to be a full, clear, and exact description of the invention, such as will enable others skilled in the art to which it appertains to make and use the same.

This invention provides an improved fire screen especially designed for preventing back firing through flame passages, and, generally stated, the invention consists of the novel construction and combination of parts hereinafter described and defined in the claim. The present application is filed as a division of the present applicant's co-pending application S. N. 168,467, filed May 14, 1917, and entitled Fire screen for explosive engines.

The invention is illustrated in the accompanying drawings wherein like characters indicate like parts throughout the several views. Referring to the drawings;

Figure 1 is a vertical section showing the fire screen applied in the transfer passage of an internal combustion engine;

Fig. 2 is a plan view showing the screen moved from working position; and

Figs. 3 and 4 are face views showing, respectively, the disk-like heat conducting plates and spacing washers of the fire screen.

Of the parts of the engine, in so far as they are pertinent, the numeral 5 indicates the cylinder, the numeral 6 the crank shaft compression chamber, and the numeral 8 the transfer passage, the latter having a transversely extended cylindrical screen seat 9.

The improved fire screen is made up of a

multiplicity of laterally spaced thin metal disk-like heat conducting plates 10, spacing washers 11 of relatively small diameter and a clamping bolt 12 provided with a head 13 and a threaded end equipped with a nut 14. The spacing washers 11 are interposed between the disk-like plates 10 and the bolt 12 is passed through the axial perforations of the said plates and washers and when the nut is tightened, the said elements are rigidly clamped together. The perimeters of the radiating plates 10 are circular and of such diameter that they closely fit the cylindrical seat 9 so that a good contact is made for the conduction of the heat from the screen to and through the walls of the cylinder.

Fig. 1 illustrates one of the many uses to which this screen may be put. In this particular use it has been found highly efficient for the purposes had in view. The screen may be cheaply constructed and may be taken out and easily cleaned from time to time.

What is claimed is:

A fire screen made up of a multiplicity of disk-like heat conducting plates, interposed spacing washers of relatively small diameter, and a clamping bolt extended axially through said plates and washers and clamping the same together, said plates, washers and clamping bolt constituting a self-contained unit, in combination with an element having a seat for said unit and also having vapor inlet and outlet passageways opening into the seat at opposite edges of said plates and along substantially the entire length of said unit.

In testimony whereof I affix my signature in the presence of two witnesses.

GRACE E. MERRILL,
Administratrix of Frank H. Merrill, deceased.

Witnesses:

CLARA DEMAREST,
EVA E. KONIG.
